US0D1082877S

(12) **United States Design Patent** (10) **Patent No.:** **US D1,082,877 S**
(45) **Date of Patent:** **** Jul. 8, 2025**

(54) **GEAR CASING**

(71) Applicant: **Flender GmbH**, Bocholt (DE)

(72) Inventors: **Christoph Messink**, Bocholt (DE);
Dirk Schroer, Rhede (DE); **Jan Andersson**, Erlangen (DE)

(73) Assignee: **Flender GmbH**, Bocholt (DE)

(**) Term: **15 Years**

(21) Appl. No.: **35/519,330**

(22) Filed: **Dec. 15, 2022**

(80) **Hague Agreement Data**

Int. Filing Date: **Dec. 15, 2022**

Int. Reg. No.: **DM/228735**

Int. Reg. Date: **Dec. 15, 2022**

Int. Reg. Pub. Date: **Dec. 15, 2023**

(57) **CLAIM**

The ornamental design for a gear casing as shown and described.

DESCRIPTION

The patent or application file contains at least one drawing executed in color. Copies of this patent or patent application publication with color drawing(s) will be provided by the Office upon request and payment of the necessary fee.

- 1. Gear casing
- 2. Gear casing
- 3. Gear casing
- 7. Gear casing
- 8. Gear casing
- 9. Gear casing
- 1.1: Left
- 1.2: Front
- 1.3: Top
- 1.4: Back
- 1.5: Bottom
- 1.6: Right
- 1.7: Perspective
- 1.8: Perspective
- 2.1: Front
- 2.2: Left
- 2.3: Top
- 2.4: Back
- 2.5: Bottom
- 2.6: Right
- 2.7: Perspective
- 2.8: Perspective
- 3.1: Back
- 3.2: Front
- 3.3: Bottom
- 3.4: Left
- 3.5: Top
- 3.6: Right
- 3.7: Perspective
- 3.8: Perspective

(Continued)

7.1: Front
7.2: Left
7.3: Top
7.4: Back
7.5: Right
7.6: Bottom
7.7: Perspective
7.8: Perspective
8.1: Back
8.2: Left
8.3: Bottom
8.4: Top
8.5: Front
8.6: Right
8.7: Perspective
8.8: Perspective
9.1: Front
9.2: Top
9.3: Left
9.4: Bottom
9.5: Right
9.6: Back
9.7: Perspective
9.8: Perspective

The designs are gear casings for housing gear units.
